UNITED STATES PATENT OFFICE.

JAMES FRASER, OF EDGE MOOR, DELAWARE, ASSIGNOR TO THE SPEAKMAN COMPANY, OF WILMINGTON, DELAWARE, A CORPORATION OF DELAWARE.

DESIGN FOR A NOZZLE.

Application filed March 5, 1928. Serial No. 25 677. Term of patent 7 years.

To all whom it may concern:

Be it known that I, JAMES FRASER, a citizen of the United States, residing at Hillcrest, Edge Moor, in the county of New Castle and State of Delaware, have invented a new, original, and ornamental Design for a Nozzle, of which the following is a specification, reference being had to the accompanying drawing, forming part thereof.

Figure 1 is a side elevation and Figure 2 is a front elevation of a nozzle, showing my new design.

I claim:

The ornamental design for a nozzle, substantially as shown.

JAMES FRASER.
